[57] CLAIM

The ornamental design for a car seat canopy, as shown and described.

DESCRIPTION

FIG. 1 is a side perspective view of a car seat canopy showing our new design. The broken line depiction of an infant in an infant car seat, positioned on a conventional car seat, is for illustrative purposes only and forms no part of the claimed design;

FIG. 2 is a side perspective view thereof;

FIG. 3 is a front elevational view thereof;

FIG. 4 is a rear elevational view thereof;

FIG. 5 is a side elevational view thereof, the opposite side being symmetrical with the side shown; and,

FIG. 6 is a top view thereof.

The broken lines on the car seat canopy represent stitching.
